FIG. 5.

UNITED STATES PATENT OFFICE

ALBERT G. HARMS, OF CHICAGO, ILLINOIS

BURIAL CASKET

Application filed April 18, 1927. Serial No. 184,463.

This invention relates to burial caskets and the object thereof is to provide a novel and practical construction by which the corpse can be conveniently raised or reposed in an 5 inclined position for placing the body on view.

The invention embodies a casket having an adjustable support which may be disposed in an inclined position to raise the head and 10 body of the deceased person, the same being preferably in the form of a false bottom having means for adjusting the bottom at the head end of the casket, either by the raising of the panel or top closure of the casket, or 15 independently thereof and which may be made in the form of a spring bottom adapted to support a mattress upon which the body is reposed, and in which provision is made for canting or tilting the body of a large or stout 20 person, so that the body may be properly accommodated in the casket and tilted slightly toward the side from which it is viewed.

Other objects and advantages will be apparent as the description proceeds.

25 In the accompanying drawings:—

Figure 1 is a longitudinal section of a casket having a false bottom and means for raising or lowering the same upon opening and closing of the panel.

30 Fig. 2 is a similar view of a centrally fulcrumed or false bed bottom having a worm for operating the same.

Fig. 3 is a sectional view taken on the line 3—3 of Figure 2.

35 Fig. 4 is a plan view of the false or bed bottom.

Fig. 5 is a sectional view taken on the line 5—5 of Figure 4.

40 Figs. 6 to 10 inclusive are views similar to Figures 1 and 2 of other forms of the invention showing other means for operating the false bottom, and

Figs. 11 and 12 are horizontal and vertical sectional views of other supporting means.

45 Referring to the drawings in detail and particularly to Figures 1 and 3, the casket 1 has a bottom 2 and a sectional molding 3, the front portion 4 of which is hinged as at 5 to drop down over the side, with the usual 50 shirred lining (not shown) if desired. The

end section 6 is hinged at 7 to swing outwardly as shown in Figure 1, while the back section 8 is hinged at 9 to swing backwardly to an inclined position and may have the top panel 10 forming part of the closure with the molding hinged thereto as shown at 11 or rigidly attached thereto in a manner common in the art. The top panel may be formed in one or two sections and the invention may also be applied to a drop side casket which is 60 also well known. The panel is adapted to be held in an upright position by a tape or cord 12 when the casket is open for viewing the body.

In accordance with my method or system and apparatus for the raising and lowering of the head and shoulders of a corpse in a coffin, casket, or burial case, there is provided a false bottom 13 which is disposed on the bottom 2 and may extend the full length of the casket or part of the length, preferably over one-half, owing to the fact that the average corpse will not bend at the waist. The false bottom may be hinged to the bottom 2 as indicated at 14, intermediately or at the foot end of the bottom of the casket and the opposite or head end is provided with means for adjusting or raising or lowering the same so as to allow the body to be placed higher for a better view and effect without the head of the corpse interfering with the closing of the casket lid and also adjustable to the desired height without requiring the insertion of devices which must be later removed.

As shown in Figure 1, a bell crank lever 15 is pivoted to one side of the casket as indicated at 16 and has one arm connected by a link 17 to the lid or panel 10 as by means of an apertured bracket 18. The other arm of the lever 15 is connected by a link 19 to the similarly extending arm of a bell crank arm 20 and the arm corresponding to the arm of the lever 15 to which the link 17 is connected has connection from its free end to the false bottom 13 pivotally by a link 21 to permit the bottom 13 to cant or tilt to the opposite side or having a brace connection extending across the width of said bottom to or near the opposite side suitably arranged to cause the false bottom to be raised or lowered uni-

formly at opposite sides. Thus when the lid or panel is open the false bottom will be raised to the desired height to support the head and upper portion of the body of the corpse in a reclining position, as well as raising the head for a better view. When the lid or panel is closed, the false bottom will be lowered by the rocking of the levers as indicated in solid and dotted lines respectively in Figure 1 to lower the false bottom so that the lid can be closed without interference.

In the form shown in Figures 2 to 5 inclusive, the false or adjustable bottom may be in the form of a bed frame or bottom 22 on which a mattress 23 may be placed. The open frame may be of angle iron or otherwise, and has a spring bottom 24 including strips 25 with springs 26 connecting the ends thereof to the ends of the frame or may be of other suitable construction. The bottom 22 is supported on a central fulcrum 27 preferably in the form of a sheet metal trough or cradle 28 having a bottom portion stamped and doubled on itself intermediately to form the fulcrum 27 transversely of the casket to rest upon the bottom 2 and the ends are directed upwardly as indicated at 29 for attachment to the sides of the bed bottom frame as shown more particularly in Figure 5. Coil springs 30 are arranged between the bottom of the trough 28 and the strips 25 of the bed bottom to accommodate and give to the body at this point, so that the body will be properly accommodated and assume a desirable posture.

In order to actuate the false or bed bottom according to this form, one end of the bottom is provided with a nut 31 engaged on a screw 32 suitably journaled in bearings 33 near the top and bottom at the head end of the casket. A shaft 34 is journaled through the head end and geared to the screw as indicated at 35 as by means of bevel gears and operated by a handle 36, so that the bottom 22 may be raised or lowered or held in adjusted position. This construction, of course, can be applied to any type of false bottom.

In Figure 6 of the drawings, the false bottom 37 is mounted on a fulcrum or pivot 38 resting on the bottom 2 intermediately and a toggle 39 is arranged between the false bottom and the bottom of the casket at the head end and held normally in a folded position by a spring 40 shown as a contractile coil spring connected to the bottom 2 and the pivot joint or joints of the sections of the toggle or toggles. One or two of said toggles may be provided and extending from the opposite side of the joint or joints are cables 41 which pass around side pulleys 42 and 43 mounted on the inside of the head end of the casket near the bottom and near the top, the cable being subsequently extended through said end and anchored to a bracket 44. In this manner the false bottom may be readily

raised in any desired adjusted position or lowered.

In Figure 7 of the drawings the false bottom 13 has a cable or braided cord 45 connected thereto at the head end and passed around a pulley 46 from which it is extended through the end and anchored to the bracket or tie member 44 as previously described.

In Figure 8 of the drawings a pneumatic or rubber air chamber 47 may be provided beneath the head end of the false bottom 13 adapted to be inflated through a valved tube 48 extended through the head end preferably near the top. This chamber is adapted to be inflated to cause it to expand and hold the false bottom at the desired height but when deflated it will collapse and permit the false bottom to be lowered.

In Figure 9 of the drawings, the false bottom is connected by a link 49 to a point on a disk 50 in the manner of a crank, which disk is in the form of a worm wheel pivoted or journaled axially at 51. A worm 52 is mounted on the inner end of a shaft 53 journaled in the head end of the casket and adapted to be turned by a handle or crank 54 so as to turn the worm gear and by its connection with the false bottom eccentrically through the medium of the link 49 to raise or lower the false bottom.

In Figure 10 of the drawings, the false bottom has attached to the head end thereof one or two hangers 55 with handle portions 56 and apertures 57 to be engaged over a series of vertically spaced pegs or angular projections 58 extending inwardly from the head end of the casket or mounted on a plate 59 secured to said end. In this case the handle portions 56 are grasped to raise or lower the false bottom, and by disposing the apertures 57 over the pegs or angular supports 58, adjustment of the false bottom may be secured or it may be lowered to the bottom 2 of the casket. One of these devices may be provided centrally or one at either side, so that the false or movable bottom may be arranged in a canted, tilted or transversely inclined position slanting to one side, or toward that side from which the body is viewed. This is especially desirable in accommodating a stout person.

In Figures 11 and 12 another supporting means is shown in which notched plates 60 are hinged as at 61 to the sides of the casket and means provided on the false bottom, such as the hangers 55 without the apertures 57, to raise the false bottom to the desired height, when the hinged plates are swung inwardly from positions against the inner faces of the sides of the casket to positions at right angles thereto, so that the side edges of the false bottom will fit in the notches 62 to secure the proper inclination. Obviously, by holding the false bottom in a supported position by the hanger 55, the plates or notches sup-

ports 60 may be swung outwardly against the inner faces of the sides of the casket to permit the false bottom to be lowered.

With a device such as described, the false bottom of the casket may be raised or inclined to dispose the head of the body in the most effective position for view or inclined transversely of the casket toward the side from which the body is viewed and to accommodate a stout person, as heretofore described. The false or movable bottom may be made of wood, metal, wire, or other material strong enough to support the corpse so that it can be raised or lowered or left in any desired position.

While I have shown several means of accomplishing the objects of the invention, it is to be understood that other forms may be provided and that modifications may be resorted to in the construction and arrangement of the parts without departing from the spirit of my invention so long as the same do not depart from the scope of the device as claimed.

25 I claim as my invention:

1. The combination with a casket having a top closure, a spring bottom fulcrumed upon the bottom of the casket and including a spring structure adapted to support a mattress, and a depressed central portion over the fulcrum and supporting said spring structure, and means at the head end of the casket and co-operating with the adjacent end of the bed bottom to raise or lower the same and hold it in an adjusted position.

2. The combination with a casket having a top closure, of a bed bottom fulcrumed upon the bottom of the casket and including a spring structure adapted to support a mattress, a depending central portion over the fulcrum, and means for adjusting said bed bottom about its fulcrum relative to the casket.

3. The combination with a casket having a top closure, of a bed bottom fulcrumed upon the bottom of the casket and including a spring structure adapted to support a mattress and a depending central portion over the fulcrum, and means at one end of the casket co-operating with the adjacent end of the bed bottom to raise or lower the same and hold it in an adjusted position.

4. In a device of the class described, a casket having a relatively stiff but warpable false bottom pivoted to the casket on a transverse axis, and means for securing said false bottom in a position of angular and of canted adjustment with respect to said axis.

5. A device as defined in claim 4, wherein said false bottom comprises a warpable frame.

6. A device as defined in claim 4, wherein said false bottom comprises a warpable spring supporting frame.

7. A device as defined in claim 4, wherein said false bottom comprises a warpable spring

frame, and has a transverse row of coil springs intermediate its ends.

8. In a device of the class described, a casket having a pivoted lid and having a false bottom pivoted therein on a transverse axis, and means connecting said lid to said false bottom whereby said bottom will be elevated about said axis when said lid is raised.

9. In combination with a casket, a false bottom adapted to support a mattress or the like, said bottom having a depressed portion intermediate its ends and serving as a transverse fulcrum upon which said bottom may be pivoted, and a plurality of coil springs seated in said depressed portion.

10. A device as defined in claim 9, wherein said depressed portion is disposed substantially midway between the ends of said false bottom, whereby the buttocks of a body resting on said false bottom will be disposed over said springs.

11. In a device of the class described, a burial casket having a false bottom fulcrumed relative to said casket on a transverse axis, said false bottom being sufficiently stiff to support a mattress or the like and at the same time being warpable whereby said bottom may be canted, and means for adjusting the elevation of said false bottom relative to said casket about said axis.
